UNITED STATES PATENT OFFICE.

ISAAC SMITH, OF BROOKLYN, NEW YORK, ASSIGNOR OF ONE-HALF TO JOHN W. ATWOOD, OF SAME PLACE.

COMPOSITION-FACED BUTTON.

SPECIFICATION forming part of Letters Patent No. 395,186, dated December 25, 1888.

Application filed October 15, 1888. Serial No. 288,154. (No specimens.)

To all whom it may concern:

Be it known that I, ISAAC SMITH, of Brooklyn, in the county of Kings and State of New York, have invented a new Improvement in 5 Composition-Faced Buttons; and I do hereby declare the following, when taken in connection with accompanying drawings and the letters of reference marked thereon, to be a full, clear, and exact description of the same, and 10 which said drawings constitute part of this specification, and represent, in—

Figure 1, an edge view half in section; Fig. 2, a section representing the introduction of 15 the back into the front; Fig. 3, an edge view half in section of the metal blank for the front, detached.

This invention relates to an improvement 20 in the manufacture of buttons in which the body is metal, but the exposed surface covered with a composition or non-metallic material applied to the blank in a plastic condition, and is an improvement upon the invention for which Letters Patent of the United 25 States No. 381,438 were granted to me April 17, 1888.

In my previous patent the blank for the 30 face of the button was of cup shape, made from sheet metal, and substantially the same as that employed for cloth-faced buttons, except that the blank was perforated with numerous holes, and so that a plastic composition applied to the face of the blank would be forced through the holes in the blank and become interlocked therewith, so that a very 35 thin coating of composition could be employed, and yet insure its secure attachment to the metal blank. The flange or the side of the cap was left uncoated and closed over the back in the usual manner for closing the face- 40 blank over the back in cloth buttons. This under the ordinary construction of buttons leaves the side of the cup or front exposed uncoated, because the coating could only extend to the point where the bend was to be made 45 in the side of the cup in closing it upon the back.

The object of my present invention is to so 50 construct the front and back that the blank for the front may be wholly covered—that is to say, so that the bending of the flange or side of the cup may be avoided, thereby en-

abling the blank for the front to be covered on its face entirely over its sides.

To this end my invention consists in constructing the blank for the front with its 55 flange or side turned inward—that is, contracted—and with a concentric rib upon the inside of the cup adjacent to the inclined flange, and a cup-shaped blank for the back, its external diameter corresponding to the 60 contracted diameter of the flange of the front, and so that as the back is forced into the front its edge will strike the said rib and be deflected outward between the said rib and the inclined flange of the front, whereby the 65 back and front will be firmly interlocked and as more fully hereinafter described.

In Fig. 3 the blank for the front is shown 70 in half transverse section detached and without the covering. It is made from sheet metal struck into cup shape, and the side or flange *a* turned back from the front and inward, so that the internal diameter of the flange at its edge is less than the internal diameter of the blank in the plane of the front. In the front 75 and adjacent to the side of the blank an internal rib, *b*, is formed substantially around the blank and concentric to the flange *a*, as clearly seen in Fig. 3. This rib leaves a space, *d*, between it and the surrounding flange *a*, 80 the adjacent surfaces of the flange and of the rib being inclined inward, as shown. The rib *b* is best formed by making a circular depression in the face of the button. The blank for the front is perforated, as in my previous 85 patent, and the blank is covered with the plastic material *e*, as seen in Fig. 2, the material extending over the edge and so as to cover the flange or side of the front, as shown. The application of the plastic material to the 90 back is best made substantially in the same manner as described in my previous patent, and not necessary to be described in this application further than to say that suitable dies are provided by which the requisite pressure is applied to the plastic material to bring it 95 to the required shape, and at the same time to cause it to enter the perforations in the front, whereby it will securely interlock therewith. The back *f* is made from sheet metal, of cup 100 shape. The external diameter of the side or flange *g* corresponds to the internal diameter

- of the outer edge of the flange *a* of the front, and so that the back may be set into the front, the flange *g* of the back strikes the outwardly-
5 inclined surface of the rib *b* in the front, and, suitable force being applied, the flange of the back is deflected over the rib *b* into the space between the said rib and the flange *a* on the front, as seen in Fig. 1, and so that the back
10 is firmly interlocked with the front. The depth of the back should be such as to permit it to be entirely inclosed within the front, as represented in Fig. 1, or substantially so. Under this construction I am enabled to cover
15 the entire surface of the front, because in the closing of the back and front together there is no bending effect produced upon the front or any part of it; hence no disturbance of the coating.
20 I do not claim, broadly, a button having an under-cut groove in its front portion, with a ring-shaped disk inserted into this under-cut recess, and so as to hold the eye portion in place, as such I am aware is not new.
25 It will be understood that I claim nothing in this application shown or described in my before-mentioned patent; but

What I do claim, and desire to secure by Letters Patent, is—

The herein-described improvement in composition-faced buttons, which consists in a metal cup-shaped blank for the front, constructed with its side or flange turned inward, so that the inner surface is inwardly inclined from the plane of the front, and the front 30 also constructed with a concentric rib upon its inside adjacent to its flange and correspondingly inclined, the outer surface of the blank covered with a composition, the said composition extending over onto the inclined 35 outer surface of the flange and so as to cover that surface, combined with a cup-shaped back, the external diameter of the flange or side corresponding to the internal diameter of the flange of the front at its outer edge 40 and forced into the front against the inclined surface of the said rib, and thereby deflected outward between the said rib and the side of the front, whereby the said back is interlocked with the front, substantially as described.

ISAAC SMITH.
